UNITED STATES PATENT OFFICE.

JOSEPH DELLER, OF NAPOLEON, INDIANA.

AUTOMATIC RAILWAY-SWITCH.

SPECIFICATION forming part of Letters Patent No. 605,599, dated June 14, 1898.

Application filed March 18, 1898. Serial No. 674,296. (No model.)

To all whom it may concern:

Be it known that I, JOSEPH DELLER, a citizen of the United States, residing at Napoleon, in the county of Ripley and State of Indiana, have invented certain new and useful Improvements in Automatic Railway-Switches; and I do hereby declare the following to be a full, clear, and exact description of the invention, reference being had to the annexed drawings, which form a part of this specification.

My invention comprises a railway-switch which is capable of being conveniently operated by a driver or motorman on a street-car as soon as he brings a grab or trip into service. The trip is applied under a car-platform a suitable distance in advance of the front wheels and is preferably operated by the depression of a treadle, which act causes the effective end of said trip to engage with a starter-plate at one end of a main shaft, the other end of said shaft being provided with a tread-plate that is normally horizontal and out of the way. This engagement of the trip with the starter-plate is only momentarily, but is sufficient to turn the main shaft a limited distance, and thereby swing the tread-plate up to a position where it will be struck by one of the front car-wheels. The contact of the wheel with said plate then completes the turning of the main shaft, and the motion of the latter is by means of bevel-gears transmitted to a counter-shaft arranged longitudinally of the track and having a crank and connecting-rod, which devices throw the switch, as hereinafter more fully described.

In the annexed drawings, Figure 1 is a plan of a street-railway track provided with my switch-operating mechanism. Fig. 2 is a vertical section at the line *z z* of the preceding illustration, the trip being about to engage with the starter-plate. Fig. 3 is a similar section, but showing said trip in the act of turning said plate in the direction of an arrow thereon. Fig. 4 is a vertical section showing the tread-plate in its normal position. Fig. 5 is a similar section, but showing said plate turned up to a vertical position and about to be struck by a car-wheel. Fig. 6 is an enlarged vertical section through the connecting-rod that communicates motion from the counter-shaft to the switch.

A A' represent grooved rails of a main track, and *B B'* are the rails of a branch track or siding, an ordinary switch *C* being located at 55 the junction of the rails *A' B'* and being connected by a rod *c* with a crank or eccentric wrist-pin *d* at one end of a counter-shaft *D*, as more clearly seen in Fig. 6. This shaft is journaled in suitable bearings, is arranged 60 parallel with the rail *A'*, and has keyed to it a bevel-gear *E*, that engages with a similar wheel *F*, fastened to the main shaft *G*, the latter being disposed at a right angle to said rail or transversely of the track. Furthermore 65 this main shaft *G* has one of its ends journaled in the rail *A'*, while its other end is journaled in a short third rail *H*, arranged comparatively near said rail *A'* and parallel therewith. Rail *H* is grooved longitudinally 70 on its upper surface, as at *h*, and one end of this groove communicates with a mortise *h'* of said rail, a starter-plate *I* being housed within said mortise. This starter-plate is secured to the main shaft *G* and has a notch *i* 75 at one corner and a similar notch *i'* at its diagonally opposite corner.

J is a flap or cover adapted to rest flatly upon the starter-plate *I* when the latter is in its normal or horizontal position, the end of 80 said flap nearest to the groove *h* being rounded off, as at *j*.

K K' are ears wherewith said flap is hinged to some stationary part of the mechanism.

L is a spring that causes the flap to remain 85 closed until intentionally opened by a car-driver or motorman.

a' is a vertical mortise in the rail *A'* to admit a tread-plate *M*, secured to the main shaft *G*, the diagonally opposite corners of said 90 plate being rounded off, as shown in Figs. 4 and 5.

N is a ratchet-wheel fastened to the counter-shaft *G*, and *n* is a pawl so engaged with said wheel as to prevent retrograde turning 95 of said shaft in case a wheel of a passing vehicle should wedge tightly against one side of the switch *C*.

b' in Fig. 6 is a slot that permits the upturned end of rod *c* to move laterally of the 100 rails *A'* and *B'* when the switch is thrown in either direction.

In Figs. 2 and 3 is a portion of the front platform of a street-car, and *o* is a hanger de-

pendng therefrom, a hook-shaped trip or grab P being pivoted to said hanger and having one end of a treadle Q connected to it. R is a spring that so elevates the treadle Q as to maintain the free end of the trip a suitable distance above the track. S in Fig. 5 is one of the front wheels of a car. When all the operative parts of my switch mechanism are in their normal positions, they are disposed as seen in Figs. 1, 2, and 4, reference to which illustrations shows that the switch C is now so set as to keep the main track open and prevent cars being run over on the siding or branch B B'. Again, it will be noticed that the starter-plate I is now completely housed within the mortise h' and is almost entirely concealed by the flap J; also, it will be observed that the tread-plate M is completely housed within the mortise n'. If a car should approach the switch in the direction of the arrow shown in Fig. 2 and it should be desired to run straight forward on the main track, the driver or other attendant on the front platform pays no attention to the trip P and simply permits it to remain in its elevated or inoperative position; but if it should be desired to run a car over onto the side track, the aforesaid attendant depresses the treadle Q at the proper moment, so as to cause the free end of the trip to swing down and traverse the longitudinal groove h of the third rail H. Consequently this groove so guides said trip as to compel its hooked end to enter the notch i of plate I and swing the latter over in the direction indicated by the arrow in Fig. 3. This swinging motion of the plate causes the flap J to turn up to the vertical position indicated by the dotted lines 40 in said illustration, the rounded end j of said flap enabling it to smoothly clear the advancing trip. Now as the plates I M are rigidly united to the main shaft G it is evident this turning up of the plate I will cause the other plate M to travel simultaneously with it. Therefore by the time the plate I has reached a perpendicular position the plate M will also be vertical, as shown in Fig. 5. Again, this motion of plate I effects a limited turning 45 of shafts G D and merely starts the throwing of the switch C toward the rail A'; but about the instant said plate reaches a vertical position the trip is disengaged from it, and for this reason some other means must be provided for completing the setting of the switch. This final setting is effected by the tread of car-wheel S coming in contact with the plate M, as suggested in Fig. 5, thereby

forcibly swinging said plate over in the direction of the arrow and retaining the switch in contact with the main rail A'. Hence it is evident the momentum of the car is utilized in the final throwing of the switch, thereby relieving the trip of this severe duty, which frequently requires considerable power, especially when the rails are covered with thick snow and ice. As the tread-plate M is thus forced down to a horizontal position the starter-plate I is also brought to a horizontal position, and its notch i is now in line with the groove h and ready to be caught by a car trip or grab. Again, as these plates have described one-half of a circle, it is evident the shafts D G have also made a half-turn in their bearings. Therefore if the next car is to be run in on the side tracks no manipulation of the switch is necessary; but if said car is to continue along the main track the trip is again operated as previously described, the result being to cause the shafts D G to 55 complete their revolutions and restore the switch to its normal position. Finally, in the drawings the stringers, cross-ties, and the covers for the shafts, gears, &c., have been omitted for the purpose of rendering the mechanism more distinct; but it is to be understood that the third rail or beam H and flap J are the only parts exposed to the wear and tear of street traffic. I claim as my invention—

1. A switch mechanism including a main shaft provided with starter and tread plates, and a counter-shaft geared to said main shaft and coupled to the switch proper, said starter-plate being adapted to be operated by a car-trip, substantially as herein described, and for the purpose stated. 95

2. A switch mechanism including a main shaft G, provided with a tread-plate M, and starter-plate I, notched at i, i', a mortised and longitudinally-grooved third rail H h h', within which mortise h, said plate I i i' is fitted, a flap J that covers this plate, a counter-shaft D d, a rod c that couples said shaft to the switch C, a spring L for retaining said flap in its closed position, and bevel-gears F, E, for communicating motion from said main shaft to said counter-shaft, all as herein described, and for the purpose stated. 100 105

In testimony whereof I affix my signature in presence of two witnesses.

JOSEPH DELLER.
